J. T. DUNN

FLEXIBLE SHAFTING

Filed June 29, 1926

Inventor
J. T. Dunn,

By Clarence A. O'Brien
Attorney

UNITED STATES PATENT OFFICE.

JOHN T. DUNN, OF NORTH ATTLEBORO, MASSACHUSETTS.

FLEXIBLE SHAFTING.

Application filed June 29, 1926. Serial No. 119,346.

The present invention relates to flexible shafting, particularly, although not necessarily, adapted for use with motor boats for driving the propeller.

- 5 The principal object of the invention is to provide a flexible shafting which will operate efficiently and in a reliable manner under the conditions found in driving the propeller of a motor boat.
- 10 Another very important object of the invention is to provide a flexible shafting which will prove strong and durable in use, one which is comparatively inexpensive to manufacture, not likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

- 25 Fig. 1 is an elevation of one embodiment of the invention, and

Fig. 2 is an end elevation thereof.

Each section of the shaft is formed with a cylindrical body 21 having conical ends 22, through the apices of which project eyes 23 and from the base of which project arcuate elongated loops 24. The eyes 23 and the loops 24 of each section are interlinked

with the respective parts of the other sections as is clearly shown in Fig. 1. It will 35 thus be seen that these loops 24 take the strain off the eyes 23 at all times, during the rotation of the shaft.

It is thought that the construction, operation, and advantages of this invention will 40 now be apparent by those skilled in this art without a more detailed description thereof. The present embodiment of the invention has been described and shown in detail merely 45 by way of example, since in actual practice it attains the features of advantage enumerated as desirable in the statement of the invention and the above description.

Numerous changes in the details of construction, and in the combination and arrangement of parts may be resorted to without departing from the spirit or scope of the invention as hereinafter claimed or sacrificing any of its advantages.

Having thus described my invention, what 55 I claim as new is:—

A flexible shafting of the class described including a plurality of sections, each section including a body having outwardly projecting conical-shaped ends, eyes at the apices of said ends, a series of arcuate elongated loops at the base of each end, the loops and the eyes of the sections being interlinked for connecting the sections together.

In testimony whereof I affix my signature.

JOHN T. DUNN.
